UNITED STATES PATENT OFFICE.

JOHN O. NEIKIRK, OF LOMBARD, ILLINOIS.

RAILROAD-CAR.

1,308,442.

Specification of Letters Patent.

Patented July 1, 1919.

Application filed June 22, 1916. Serial No. 105,188.

To all whom it may concern:

Be it known that I, JOHN O. NEIKIRK, a citizen of the United States, residing at Lombard, in the county of DuPage and 5 State of Illinois, have invented certain new and useful Improvements in Railroad-Cars, of which the following is a specification.

My invention relates to improvement in railway cars. The object and nature of the 10 invention is set forth in the following description and drawings in which,

Figure 1 is a plan view of one end of the underframe of a car constructed according to my invention.

Fig. 2 is a cross section of the lower portion of the central part of the car through the longitudinal hopper.

Fig. 3 is an end view of the lower part of the car.

Fig. 4 is a cross section through the underframe of the car on the line 4—4 of Fig. 5.

Fig. 5 is a central longitudinal section of the end part of the car.

My invention has been designed primarily 25 for application to cars having a central hopper extending longitudinally of the car between the bolsters; but in its broad aspect the invention is not restricted to cars of 30 that type. Hopper cars of the type referred to are illustrated and described in my prior Patents, Nos. 1,098,748 and 1,112,644, granted June 2, 1914, and October 6, 1914, respectively, and in Patent No. 761,674, granted 35 to H. S. Hart and O. W. Meissner June 7, 1904, and No. 820,046, granted to E. S. Hart May 8, 1906. The cars described in the Hart and Meissner and Hart patents referred to have underframes constructed of wood, and 40 in the structures of the other two patents the underframes are constructed of steel.

In railway cars of all types it is necessary 45 that the longitudinal members of the underframe support not only the vertical load, but that these members should also sustain the pulling and buffing stresses. In the construction of cars of the type above referred to provided with longitudinal central hoppers, the center sill, upon which reliance is 50 usually placed to sustain the buffing and pulling stresses, is omitted, by reason of the fact that it is necessary to leave the center of the hopper unobstructed. In such cars, 55 therefore, it is necessary to transmit the pulling and buffing stresses from the draft

sills—which, of course, must lie along the longitudinal center line of the car—to longitudinal members sufficiently remote from the car center to provide the necessary width 60 for the hopper.

Formerly the size of cars ordinarily used and the weights which they were designed to carry were not as great as at present, and satisfactory results were obtained by 65 constructing the longitudinal members of the underframes of wooden beams, as shown in the Hart and Meissner and Hart patents above referred to. With the increasing size of cars, and the increasing weight of the 70 loads carried, difficulties were encountered in the use of wooden sills, and in recent years it has become customary to construct such cars with steel underframes, as shown in my two patents above mentioned. 75

While the use of steel in such cars has resulted in the provision of an abundance of strength to resist the stresses incident to service, the cost of the cars has been greatly increased, and at times the cost of steel has 80 reached such points as to interfere seriously with the construction of such cars.

I have found that longitudinal car sills of wood possess an abundance of strength to carry the vertical load due to the weight of 85 the car and contents and that failure to properly sustain the pulling and buffing stresses is the principal source of weakness of wooden sills. In cars constructed with steel longitudinal sills, the amount of steel 90 employed is vastly in excess of that necessary to take care of the pulling and buffing stresses, such excess being necessary to efficiently carry the vertical load. The object of my invention is to construct a car in 95 which wood is employed to carry the vertical load and in which sufficient members of steel are provided to sustain all of the pulling and buffing stresses.

While the car illustrated in the drawings 100 is of the central longitudinal hopper type, it will be apparent that my invention, in its broader aspect, may be used in cars of other forms.

In the drawings, I have illustrated a car 105 embodying my invention in one form. The bolster A is of metal and is shown as a casting, extending continuously from one side of the car to the other and having the center bearing 1, formed integral therewith. Also 110 formed integrally with the bolster, are flanges 2—2, reinforced by braces 3—3, the

flanges 2—2 projecting outwardly from the bolster, that is, toward the end of the car.

The metal draft sills 4—4, shown in the present instance as channels, are riveted to the flanges 2—2, and are further secured to the bolsters by means of the gusset plates 5—5, which are riveted to the draft sills and the top of the bolster, respectively. At their outer ends, the draft sills are secured 10 to the metal end sill 6, the connection being reinforced by means of gusset plates 7—7.

Projecting from the inner side of the bolster, that is, the side toward the center of the car, are angular brackets or flanges 8—8, 15 having vertical and horizontal webs, as most clearly shown in dotted lines in Fig. 4, and as further indicated in Figs. 1 and 5. The brackets 8—8 are located at some distance from the center of the car and are provided 20 for the purpose of securing means of connection between the longitudinal metal sills 9—9 and the bolsters.

In the present instance, the longitudinal metal sills 9—9 are angle irons having their 25 flanges lying against the vertical and horizontal flanges of the brackets 8—8, to which they are secured by means of rivets. The longitudinal metal sills 9—9 extend from bolster to bolster, and being attached to the 30 bolsters, serve to carry the pulling strains imposed upon the car.

The bolsters A, draft sills 4 and longitudinal sills 9 are all located in substantially the same plane, provision being thus made 35 for transmitting the pulling stresses through the car in as direct a line as possible, while still leaving space at the center of the car for the hopper.

Inasmuch as the sills 9—9 are out of line 40 with the draft sills, I have strengthened the central part of the bolster through which the pulling and buffing stresses are transmitted from the draft sills 4—4 outwardly to the sills 9—9. In the present instance the necessary strength is provided by vertical webs 20—20 connecting the top and bottom plates of the bolster, the webs 20—20 extending from the center of the bolster out to the brackets 8—8, as clearly shown in Fig. 1. 45 Beyond the brackets 8—8 sufficient strength is imparted to the bolster by the single central web 21. In cars as ordinarily constructed, the bolsters merely maintain the vertical load, but in my improved car the 50 bolsters transmit the pulling and buffing stresses from the central part of the car, *i. e.* from the draft sills outwardly to the sills 9—9 which fact gives use to the novel centrally strengthened bolster above described. 55 Of course, it will be apparent that the central part of the bolster may be strengthened by distributing and arranging the metal in many different ways, that above described being merely illustrative of one preferred 60 structure.

For the purpose of providing means of attachment and assisting in sustaining the hopper, I have provided wooden fillers 10, lying inside of the angle metal sills 9, the wooden members 10 extending from one 70 bolster to the other.

The vertical load sustaining elements of the car are wooden longitudinal sills 11 and 12 and 13, lying above the bolsters and extending from one end sill to the other. Ex- 75 tending from the end sills to the ends of the hoppers, I have also provided short wooden sills 14, lying directly above the draft sills and bolster.

The wooden longitudinal sills 11, 12, and 80 13, serve to sustain the vertical load, but the wooden sills are relieved of the pulling and buffing stresses, which latter are carried by the draft sills and metal longitudinal members 9—9.

While I have described one specific embodiment of my invention, it will be apparent that the application of my invention is not limited to the specific forms herein illustrated and described.

What I claim is:

1. A car underframe comprising a metallic subframe having spaced longitudinal sills for the reception of a hopper and being out of line with the draft sills and extending 95 only between the bolsters, said subframe including bolsters, the central parts of which have double supporting flanges and the outer ends of which have single central supporting flanges carrying the horizontal 100 stresses, and a superframe comprising the longitudinal sills resting on the bolsters and transmitting vertical load to the bolsters.

2. In a car underframe, a metallic subframe comprising bolsters, draft sills attached to said bolsters, longitudinal sills connecting said bolsters, said longitudinal sills being out of line with and farther from the center of the car than said draft sills, the central part of said bolster having double supporting flanges to transmit the buffing and pulling stresses outwardly from the draft sills to said longitudinal sills, the outer ends of the bolsters having single central supporting flanges, and a wooden superframe 110 comprising longitudinal sills resting on the bolsters and adapted to transmit the vertical load thereto.

3. In a car underframe, a metallic subframe comprising bolsters, draft sills attached to said bolsters, longitudinal sills connecting said bolsters, said longitudinal sills being out of line with and farther from the center of the car than said draft sills for the reception of a hopper, the central part 120 of said bolster having double supporting flanges to transmit the buffing and pulling stresses outwardly from the draft sills to said longitudinal sills, the outer ends of said bolsters having single central supporting 125 flanges.

flanges, and a wooden superframe comprising longitudinal sills resting on the bolsters and adapted to transmit the vertical load thereto, said metallic subframe being 5 adapted to sustain all of the buffing and pulling stresses.

4. A metal car bolster, said bolster being of sufficient strength throughout its length to sustain the vertical load of a car and its 10 contents, and the central part of said bolster having double supporting flanges to trans-

mit all of the pulling and buffing stresses imposed on a car from the center of the bolster to points intermediate the center and ends thereof, the ends of said bolsters having single central supporting flanges. 15

In testimony whereof, I have subscribed my name.

JOHN O. NEIKIRK.
